AUTOMATICALLY FED FURNACE

Hugh W. Sanford and Alfred F. Sanford, II,
Knoxville, Tenn.; said Alfred F. Sanford, II,
assignor to said Hugh W. Sanford

Application December 8, 1941, Serial No. 422,188

33 Claims. (Cl. 110—32)

The invention relates generally to furnace structures adapted for the burning of solid fuel and primarily seeks to provide a novel furnace structure embodying a longitudinal fire pot open or openable at one end for ash and clinker discharge, reciprocable means for positively forcing fuel and ash along the fire pot toward said discharge end, means for feeding charges of fresh fuel so that a column of fresh fuel will reach approximately to the bottom or grate of the combustion chamber, and in front of and adjacent to the forcing means, power means for operating the fuel feeding means and the forcing means, and means for so timing and controlling the operation of the fuel feeding means and the forcing means as to meet all heat demands and yet assure against burning out of the fire, the discharging of any substantial quantity of unburned fuel with the ashes, and to prevent the heat waste that occurs when ashes are burned into clinkers.

An object of the invention is to provide in a furnace of the character stated a dual timing control effective to automatically provide a predetermined definite number of fuel charge feedings in a given interval of time for maximum combustion operation of the furnace, and to provide a variable predetermined lesser definite number of fuel charge feedings in a like interval of time for idling operation of the furnace.

Another object of the invention is to provide a furnace embodying a dual timing control of the nature stated including two fuel charge feed timing devices and thermostatic or pressure control means for rendering said devices selectively effective according to heat demand.

Another object of the invention is to provide a furnace of the character stated in which the dual timing controls and additional control means are so cooperatively arranged that the latter will dominate control when a fresh fire is being started and will cause continuous fuel charge feeding until a predetermined congestion of fuel mass is established in the fire pot, after which normal control will be taken over by said dual timing controls and maintained thereby until such time as rapid fuel combustion may have reduced fuel mass congestion to a predetermined minimum at which time continuous fuel charge feeding will again be temporarily occasioned.

Another object of the invention is to provide a furnace of the character stated in which said additional control means includes a novel door structure yieldably obstructing discharge of ash and clinkers, and control switch means actuated by movement of the door.

Another object of the invention is to provide a furnace of the character stated in which is embodied a fire pot flared at its side walls and offset at its bottom so as to reduce friction resulting from fuel mass contact and also eliminate danger of clogging the fuel mass forcing means.

Another object of the invention is to provide novel means for directing primary air into the combustion chamber within the fire pot through novel non-clogging openings in the bottom and side walls of said fire pot.

Another object of the invention is to provide novel means for providing secondary air above the fuel combustion zone in the fire pot.

Another object of the invention is to provide novel means for causing smoke and gases passing off above freshly fed green fuel located exclusively in the receiving end of the fire pot to be directed toward the opposite end of the fire pot and over incandescent fuel in the combustion zone, thereby to be consumed over said combustion zone.

Another object of the invention is to provide novel means for causing the primary and secondary air to be preheated before effective delivery thereof.

Another object of the invention is to provide a furnace of the character stated in which the fuel feeding means and the fuel mass forcing means comprise a common prime mover, a reciprocable pusher, a reciprocable feeder slide, a crank shaft driven by the prime mover, and connections between said pusher and slide and said crank shaft for reversely and positively reciprocating the pusher and slide.

Another object of the invention is to provide means of the nature stated for positively reciprocating the pusher and the slide in which the driving connections can be readily adjusted to vary the effective stroke movements of the slide.

Another object of the invention is to provide means of the character stated for adjusting the effective stroke movements of the fuel feeding slide including devices for causing all variations in the stroke of the slide to be effected at the retraction end of the slide stroke, thereby to cause the slide always to be advanced to a predetermined position regardless of stroke adjustment.

Another object of the invention is to provide a fire pot of the character stated including an ash discharge door for yieldably resisting discharge of ashes therethrough as a result of pressure exerted on the fuel mass by the fuel mass pusher, and means for varying the amount

of resistance offered by said door thereby to vary the depth of the fuel bed maintained in said fire pot.

Another object of the invention is to provide in a fuel feeding means of the nature stated a yieldable gate through which the fuel charges are forced by the slide and composed of slender, closely spaced yieldable fingers which will permit lump passage without free outpouring of finer fuel particles.

Another object of the invention is to provide in a fuel feeding means of the character stated a novel swingable flap displaceable during each fuel charge feeding but which normally serves to protect fuel in the hopper from radiant heat from the combustion chamber.

Another object of the invention is to provide in a furnace of the character stated a novel fuel mass pusher structure, novel means for preventing clogging of the pusher, and novel means for discharging any fuel which might force past said pusher into the tunnel in which the pusher operates.

Another object of the invention is to provide in a furnace of the character stated means for always discontinuing movement of the fuel feeding slide and the fuel mass advancing pusher in predetermined positions, preferably but not necessarily with the slide retracted and the pusher in its advanced position.

Another object of the invention is to provide in a furnace of the character stated a fan for supplying air for the combustion of the fuel, and control means for causing the fan to operate continuously while the furnace operation is under the control of the fast timer equipment, and intermittently when the furnace operation is under control of the slow timer, that is to say when idling.

With the above and other objects in view which will more fully appear the nature of the invention will be more clearly understood by following the description, the appended claims, and the several views illustrated in the accompanying drawings.

In the drawings:

Figure 1 is a central vertical longitudinal sectional view of a furnace embodying the invention.

Figure 2 is a vertical cross section taken on the line 2-2 on Figure 1.

Figure 3 is a vertical cross section taken on the line 3-3 on Figure 1.

Figure 4 is a horizontal section taken on the line 4-4 on Figure 1.

Figure 5 is a right side elevation of the furnace.

Figure 6 is a fragmentary end elevation of the fire pot showing the mounting of the ash door actuated switches.

Figure 7 is a fragmentary right side elevation of the parts shown in Figure 6.

Figure 8 is a fragmentary vertical cross section showing a modified form of the arch providing a restricted passage for smoke and gases over the incandescent fire bed.

Figure 9 is a vertical cross section taken on the line 9-9 on Figure 8.

Figure 10 is a fragmentary enlarged detail horizontal section taken on the line 10-10 on Figure 1 through the lower pivot mounting of the fuel feeding slide reciprocating lever.

Figure 11 is an enlarged front face view of one of the limit switches.

Figure 12 is a right end elevation of the limit switch shown in Figure 11, parts being broken away and in section.

Figure 13 is a rear elevation of the limit switch shown in Figure 11, an adjustment of the switch position being indicated in dotted lines.

Figure 14 is an enlarged side elevation showing the position switch mounting.

Figure 15 is a vertical cross section taken through the axis of the position switch actuating cam.

Figure 16 is a diagrammatic view illustrating 10 the electrical connections of the various control devices for use in a furnace adapted for the burning of other than anthracite coal, the ash discharge gate operated switches being omitted.

Figure 17 is a view similar to Figure 16 and 15 illustrates the connection of the control devices in a furnace adapted for the burning of anthracite.

Figure 18 is a view similar to Figure 16 and 20 illustrates the electrical connections of the various control devices for use in a furnace in which the ash discharge gate operated switches are included.

In the example of embodiment of the invention herein disclosed, 5 designates the floor or bottom upon which rests an open base frame 6. The frame is closed at the sides and rear by a sheet metal casing structure 7, and its open front is closed by an ash removal door 8. The casing 7 is provided with a removable side panel 9 through which access may be had to the interior 30 of the base structure and the mechanism therein.

A fire pot generally designated 10 is mounted in spaced relation within the base frame, said fire pot including side walls 11 which are flared slightly in the forward direction and which depend 25 from supporting flanges 12 resting upon the base frame 6. The fire pot also includes a fire bed supporting bottom generally designated 13 and which is flange-supported, as at 14, between the lower edges of the side walls 11. See Figures 1 40 and 2.

The fire pot bottom or "grate" preferably is formed of individually removable cross bars or sections having air ports 15 provided therein in the staggered relation best illustrated in Figure 4, 45 and these cross bars or sections are formed to provide an overhanging roof or hood structure 16 overlying each of the ports. It will be observed that the roof or hood structures are projected forwardly thereby to cause the ports to open upwardly and forwardly into the fire bed, or, in other words, in the direction in which the fuel mass is advanced over the supporting bottom 13 in a manner later to be described.

The particular construction and arrangement 55 of the fire pot bottom cross bars provide other advantages. By proper regulation of the size and locations of the openings or air ports 15 in the bottom, it is possible to introduce the relative amount of air desired in each different part of the fire pot. Thus it is possible to either intensify or retard the combustion rate at will and in any certain part of the fire pot relative to some other part. This feature will be found very advantageous. The hood structures 16 also tend to break up the fuel mass which passes over the fire pot bottom from the receiving end thereof to the ash discharging end thereof and to permit the easier passage of the air through the fuel mass.

70 It is also preferred that the fire pot bottom be inclined downwardly toward the ash discharging end thereof in the manner illustrated in Figures 1 and 8 of the drawings. By thus inclining the bottom 13, and by flaring the side walls 11 in the manner hereinbefore stated, less resistance

to movement of the fuel mass within the fire pot is offered and the effort necessary to be expended by the motor which drives the pusher 24 is materially reduced. It is to be understood that the amount of the flare of the side walls and the amount of the forward and downward inclination of the fire pot bottom may be varied according to the nature of the particular installation and the type of fuel to be used. The use of an inclined bottom in the fire pot will be found very advantageous in installations where it is desirable at times to maintain a long but thin fuel bed.

It will be observed that the fire pot is longitudinally directed and preferably substantially U-shaped with the front end thereof through which ashes and clinkers are adapted to be discharged sloped as at 17. The sloped, ash and clinker discharging end of the fire pot is equipped with a gravity closed ash discharging door 18 which is hingedly supported at its upper end as at 19. An adjustably mounted weight 20 is carried by the door 18 at its lower end, and by adjustment of this weight the resistance to opening of said door can be varied to suit the variations in operating conditions occasioned by the use of different forms of fuel, and different lengths of fire pot. It is also possible to vary the depth of the fire bed in the fire pot for a certain length by increasing or diminishing the resistance to opening of the ash discharging door, and by varying the downward slope of the bottom of the fire pot. It should be understood that for a certain downward slope the greater the resistance to opening of said door, the greater will be the depth of the fire bed being advanced over the fire bed supporting bottom to be ultimately discharged in the form of ash and clinkers through the discharge door 18. However, the height of the fuel bed is never permitted to be greater than the height of the pusher plate 24.

Primary air for the combustion of the fuel is delivered through the bottom ports 15 and it will also be observed by reference to Figures 1 and 2 of the drawings that the side walls 11 of the fire pot also are provided with longitudinal, primary air admitting ports 21 which are disposed just above the bottom 13. The side ports 21 are outwardly and upwardly inclined and have air scoop ledges 22 bordering their exteriors in position for guiding primary air thereinto. The ledges 22 also are effective to prevent falling of ashes into the air spaces. The manner in which the primary air is delivered to the ports 15 and 21 will be described later.

The fire pot is extended rearwardly at the bottom and sides to provide a tunnel 23, and in order to provide for the advancement of the fuel mass through the fire pot and the advancement of suitably timed fresh charges of fuel according to the present invention, a fuel mass pusher 24 is reciprocably mounted in this tunnel. See Figures 1 and 4. The pusher 24 comprises an upwardly and forwardly inclined pusher plate which terminates at its lower edge in a downwardly and forwardly inclined and sharpened step portion 25. The sharpened step preferably drags over the floor of the tunnel 23 during reciprocation of the pusher and is effective to dislodge any fuel tending to adhere to the tunnel floor. At its upper extremity the pusher plate merges into a horizontally and rearwardly extended shelf portion 26 which effectively serves to support any fuel falling thereon during advancement of the pusher plate and to prevent falling of fuel behind

said plate. Being upwardly and forwardly inclined, the pusher plate 24 serves to shape the fuel mass engaged thereby in the fire pot and tends also to keep the fire bed at a low level. Thus there is small possibility that the fire bed will build up and tend to flow over onto the top 26 of the pusher plate during its forward movement.

It will be observed by reference to Figure 1 of the drawings that the floor 27 of the tunnel 23 which is engaged by the lower, step portion of the pusher plate, is disposed at a slightly higher level than the main fire bed supporting surface of the fire pot bottom 13. By thus offsetting the fire pot bottom it is more difficult to cause a jamming of the pusher 24 by the adherence of fuel to the fire bottom or by reason of the presence of jammed clinkers in the bottom of the fire pot.

It will also be observed that the tunnel floor 27 is provided with a discharge opening 28 disposed just behind the limit of retraction of the pusher plate 24, and this opening will serve to discharge any bits of fuel which might find their way past the pusher plate. It should also be observed that the rearmost primary air intake ports 15 are disposed well ahead of the most advanced position of the pusher plate 24 as illustrated in Figure 1. By reason of this arrangement of the parts the danger of sticking of fuel to the fire pot bottom just in advance of the pusher plate is reduced to a minimum and leakage of primary air and smoke rearwardly past the pusher plate is effectively guarded against.

An upper cross wall 29 is provided at the rear of the fire pot and this cross wall preferably but not necessarily is disposed on an upward and forward inclination as indicated in Figure 1 and in position for lining up with the pusher plate 24 when that plate is in its most advanced position as illustrated in said Figure 1. The upper cross wall 29 serves to prevent coal from falling over the front face of the pusher plate 24 when it is in its most advanced position, and this plate also serves to protect the fuel in the hopper from radiant heat from the fire bed. While it is preferred that the wall 29 be inclined in the manner stated, it is not necessary that this wall be so inclined.

The pusher is equipped with a plunger 30 which extends rearwardly from the center thereof and is slideable in a bearing 31 provided therefor and guiding same, and preferably supported upon the tunnel floor 27.

The fire pot generally designated 10 opens upwardly into a generally square body 32 which in this particular illustration is surrounded by a sheet metal casing 33 forming an air space 34 in which air is heated by contact with the heated walls of said head. Air thus heated in the space 34 is directed to rooms or other spaces to be heated through a duct or ducts 35 and may be returned through a duct or ducts 36 for reheating. It is to be understood that a separate circulating fan may be employed for forcing circulation of this air, but since the provision of these ducts and circulating fans of this nature are well known in the art, it is thought to be unnecessary to illustrate the fan in detail herein.

A flue 37 leads upwardly from the rear portion of the body 32, and a fire brick dome 38 is disposed across the rear portion of the head 32 between the fire pot and the flue in the manner best illustrated in Figure 1. The dome 38 extends over slightly more than the rear half por-

tion of the fire pot, and a transverse fire brick wall or arch 39 depends from the foremost edge of this dome and terminates just a few inches above the fire pot so as to provide a restricted passage or space 40 between the lower extremity of said arch and the fire bed. By reason of the provision of the dome 38 and the arch 39 smoke and gases arising from those fresh fuel charges which are of a volatile nature and deposited at the rear end of the fire pot in a manner later to be described curl upwardly and forwardly under the dome 38 and are then forced downwardly into contact with the incandescent fuel bed while passing through the restricted passage 40 toward the flue 37. See Figure 1. In this manner the gases and smoke are effectively heated so that the introduction of fresh oxygen in the form of secondary air will complete their combustion, and the improved furnace operates substantially in smokeless fashion.

An ash collecting pan 41 is supported on the floor 5 beneath the advance or discharge end of the fire pot 10 and ashes, and perhaps some clinkers, accumulating in this pan can be conveniently removed through the ash door 3.

The pusher tunnel 23 is in part defined by a top wall 42 which forms a slide support for a fuel feeder slide 43 which is horizontally reciprocable in a feedway 44 provided in the manner best illustrated in Figures 1 and 3 of the drawings. The feedway 44 is disposed beneath the delivery opening of a fuel hopper or magazine 45 having a downwardly and forwardly sloping rear bottom wall 46, downwardly and inwardly sloping side bottom walls 47, and a vertical front wall 48. It will be obvious that so long as a supply of fuel remains in the hopper or magazine 45 the lower extremity of the hopper and the feedway in advance of the slide 43 will be filled with fuel, and a charge of this fuel will be delivered from the hopper at each forward movement of the slide 43.

Fuel is yieldably retained in the lower portion of the hopper by a yieldable gate structure in the nature of a transverse supporting bar 49 and preferably depending, closely spaced and fairly flexible spring steel fingers 50 which extend down into close proximity with the slideway bottom 42. These fingers are considerably longer than the largest dimension of the largest lump of fuel likely to be fed into the fire pot so that the fingers will not be bent out abruptly and get permanently "set" out of shape when the top of the supporting bar 49 is securely fastened to the main structure. Each time the fuel feeding slide 43 is advanced the fingers 50 yield to permit passage of a charge of fuel therethrough, and when the slide is retracted these fingers return to, or substantially to the vertical position illustrated in Figure 1. By reason of the provision of this novel form of yieldable gate, coal lumps can be forced through the gate and the individual fingers will yield in conformity with the shape of the extra large piece and at the same time to prevent outpouring of fine fuel particles at each side of the discharging lump. The yieldable gate 50 permits the intended feeding of solid fuel charges without forcing the slide 43 to break up any lumps which might be present in the coal. In other words, the closely spaced yieldable fingers 50 permit the passage of lumps where otherwise it would be necessary for the slide 43 to crush such lumps or stall the mechanism. This results in a large saving in potential power since it is unnecessary to use a motor capable of crushing lumps, and it also

makes it possible for foreign matter such as railroad spikes or rocks to be passed through the furnace and discharged therefrom without trouble or damage.

Just in front of the yieldable gate structure 49, 50 there is provided a solid flap 51 which is hingedly supported at its upper edge across the feedway. This flap also yields at advancement of the feed slide 43 to permit passage thereunder of each charge of fuel, and upon retraction of the slide this flap returns to its normal position illustrated in Figure 1. Positioned in the manner illustrated, the flap 51 effectively serves to protect the gate 50 and the fuel in the feedway 44 and the hopper against direct contact of heat from the combustion chamber in the fire pot 10.

The fuel charges delivered by the intermittent advancement of the feed slide 43 always are less in volume than the volume of the receiving space provided therefor by retraction of the pusher plate 24. Each such charge is deposited by the forward movement of the slide 43 and deposited generally speaking either in front of the retracted pusher face 24 or on top of the shelf portion 26 and in front of the downwardly inclined wall portion 52 and in such fashion that when the pusher 24 is completely retracted into the advance portion of the tunnel space 23, all of the fresh fuel charge will be located in front of the pusher 24. Then as the pusher 24 advances this fresh fuel charge is forced forwardly by said pusher into the rear end of the fire pot and against the fuel mass therein in the manner illustrated in Figure 3 of the drawings. It will be noted that each fuel charge thus forced into the fire pot occupies a substantially vertical layer reaching down to the supporting surface of the fire pot bottom.

It has been found advantageous to introduce 40 relatively small charges of fresh fuel at a time and introduce correspondingly more charges per hour. For instance, it has been found that in a small fire pot which has been designed to consume about 25 lbs. of coal per hour at full capacity it is advantageous to feed about 12 ounces of coal at a time at each charge, and when running high capacity, therefore, to have 30 charges fed during each hour.

The fuel feeding slide 43 includes a rearwardly 50 and horizontally extended top wall 53, and the bottom edge thereof is equipped with a forwardly and downwardly sharpened step 54 similar in formation and function with the step portion 25 of the pusher plate 24. The top wall 53 of the feeder slide 43 serves to support fuel in the hopper bottom during each forward projection of the slide 43 and by this means effectively prevents discharge of fuel behind the slide proper 43.

The fuel feeding slide 43 is equipped with a plunger 55 which extends rearwardly from the center thereof and is slidable in a bearing 56 provided therefor and is preferably supported upon the top wall 42 of the pusher tunnel.

Access to the fuel feedway 44 may be had 65 through a suitable door 57 in the casing structure and best illustrated in Figure 5 of the drawings.

It will be observed by reference to Figures 1 and 2 of the drawings that a primary air casing 58 is suspended beneath the fire pot 10. This casing is formed to provide a horizontal duct 59 extending in spaced relation to the fire pot bottom 13 and beneath all of the air ports 15 therein, but it will be noted that this duct is closed across its top portion and does not deliver air directly into said openings.

A fan 60 delivers air into the rear end portion of the duct 59, and this fan is driven by a separate motor 61.

Side plates 62 extend upwardly from the lateral extremities of the duct 59 and in laterally spaced relation to the side walls 11 of the fire pot. Intermediate side plates 63 are disposed in spaced relation between the side plates 62 and the adjacent fire pot side walls 11, and the duct 59 communicates upwardly into the space provided between the adjacent side plates 62 and 63. It will be observed by reference to Figure 2 of the drawings that the intermediate plates terminate at 64 well below the horizontal supporting flanges 12 of the fire pot, and by reason of the particular relation of these side plates, a tortuous passage 65 is provided through which primary air for introduction into the bottom of the fire pot through the side ports 21 and the bottom ports 15 first passes upwardly at each side from the bottom duct 59 between the spaced plates 62 and 63 at the respective sides, and thence downwardly between the plates 63 and the respective side walls 11 of the fire pot. In passing downwardly the air is scooped into the side openings 21 by the deflectors 22, and the air which passes these deflectors passes into the space 66 directly beneath the fire pot bottom 13 and thence upwardly and forwardly through the ports 15. By directing the primary air in the particular manner stated, this air is preheated while passing in contact with the fire pot side walls 11, and this contact serves the double purpose of tending to cool said side walls.

A secondary air duct 67 leads from the main bottom duct 59 into the fire brick wall or arch 39 where it delivers into a manifold 68 provided in said arch. From the manifold, the secondary air is delivered through a multiple of individual ducts 69 through the bottom edge of the wall or arch 39 and into the restricted space immediately beneath said arch. See Figures 1 and 2. It should perhaps be noted here that for anthracite firing, no secondary air is needed. This means of providing secondary air is designed primarily for furnaces in which the burning of volatile bituminous coal is intended.

The casing 33 is also provided with a side door 70 through which access may be had into the interior of the dome structure above the fire pot for fire inspection purposes, for the laying of a new fire, or for the replacing of the fire arch or cross wall 39.

As an example of means for suitably reciprocating the pusher and the feed slide, there is illustrated a crank shaft 71 which is rotatable in bearings 72 provided therefor and supported on the floor 5. Rotation may be imparted to the crank shaft 71 by a motor 73 and the speed of the motor is reduced through suitable reduction gearing generally designated 74 so that the crank shaft is rotated preferably at approximately one revolution every two minutes. It is found by experience that the slow rotation of the crank shaft with the consequent slow movement of the pusher 24 and the feed slide 43 provides better combustion conditions in the fire box. The crank shaft is provided with a relatively short crank 75 which is effective for driving the pusher 24, and with a longer crank 76 which is effective for driving the fuel feed slide 43. The particular crank shaft speed referred to is but an illustrative example effective to impart reciprocation to the pusher and the feed slide at a maximum rate of thirty reciprocations per hour, and is not to be construed

as a limitation upon the nature or scope of the invention.

While crank shaft, lever and link connections are herein shown and described as the means for imparting positive reciprocation to the pusher 24 and the slide 43, it is to be understood that any other acceptable means can be employed for imparting the desired fuel feeding movements to these parts.

The pusher plunger 30 is slot and pin connected, as at 71, with the upper end of a lever 78 which is fixedly pivoted at its lower end, as at 79, and is pivoted intermediate its ends, as at 80, with a thrust link 81 connected with the crank 75.

The feed slide plunger 55 is slot and pin connected, as at 82, with the upper end of a lever 83 which has a lost motion pivot connection at its lower end in a variable length slot 84 and is

pivotaly connected intermediate its ends, as at 85, with a thrust link 86 which is connected at its forward end with the crank 76. The slot 84 is formed in a fixed support 84a and the length of the slot can be varied by adjustment of a screw 84b. It will be obvious that as the crank 76 is rotated the rocker 24 and the fuel

shaft 71 is rotated the pusher 24 and the fuel feeding slide 43 will be reversely reciprocated. In other words, each time the pusher plate 24 is advanced to its foremost position illustrated in Figure 1, the fuel feeding slide 43 will be retracted to its rearmost position illustrated in Figure 1, and vice versa. By reason of the provision of the pivotal connection at the lower end of the lever 83 in the lost motion slot 84, the forward stroke limit of the slide 43 will remain constant at the

juncture of the horizontal wall portion 42 and the forwardly and downwardly inclined wall portion 52, while the retraction stroke limit of this slide may be varied by adjustment of the screw 84b, or, in other words, by adjustment of the length of the slot. It will be understood that each time the link 86 is thrust rearwardly it will move

time the link 66 is thrust rearwardly it will move the lower end of the lever 83 along the slot 84 without imparting movement of retraction to the slide 43 until the pivot pin at the bottom of the lever 83 engages the variable end of the slot, namely, the screw 84b, at which time the lost motion movement of the lower end of the lever

will be stopped and movement of the lever 83 will become effective to impart movement of retraction to the slide 43. It will be obvious that the shorter the length of the slot 84, the longer will be the length of the effective stroke imparted to the slide 43, and the longer the slot the greater will be the lost motion movement of the lower end of the lever 83 and the shorter the effective or fuel feeding stroke imparted to the slide 43.

By definitely fixing the forward limit of the slot 84, the forward stroke limit of the slide movement is fixed at the point hereinbefore described, and thus, regardless of the length of feed stroke being imparted to the slide 43, the forward limit of the slide movement is fixed at a point where it will surely remove all coal from the advance portion of the wall 42 and thereby overcome any tendency of coal lumps to hold the flap 51 open so that such coal might become ignited by radiant heat from the fire pot and burn up into the hopper.

1 A timing switch setting collar 87 is adjustably
2 secured to the pusher plunger 30 in the manner
3 best illustrated in Figures 11 and 13 of the draw-
4 ings. This collar has two actuator fingers 88
5 projecting in opposite directions laterally there-
6 from in position for actuating or setting the two
7 timing switches which form a part of the means

for automatically controlling the furnace, it being understood that one of these switches serves to provide for a predetermined definite number of fuel charge feedings and advancements in a given interval of time for maximum combustion operation of the furnace, and the other thereof serves to provide for a predetermined lesser definite number of fuel charge feedings and advancements in a like interval of time for idling operation of the furnace. The fast timer is generally designated 89 and the slow timer is generally designated 90. Since both of these timing units are identical in construction and vary only in the adjusted positions of the circuit controlling switch portion thereof, a detailed description of one of the units will suffice for both of them.

Each timer unit comprises a bracket having a base 91, an upstanding front wall 92, and a parallel rear wall 93, and is rigidly supported above the floor 5 as at 94. A cross shaft 95 is rotatably mounted in the bracket and is extended through the front wall 92 and provided with a position adjusting handle 96. The handle carries a spring pin 97 which may be engaged in any one of a plurality of selective position retaining recesses 98 formed in the front wall 92. A casing 99 is secured upon and movable with the shaft 95, and an independent rotor 100 is rotatably mounted in and projects rearwardly from the casing. The rotor 100 has a crank arm 101 attached thereto, and this arm depends in position for being engaged and moved rearwardly by the respective one of the actuator fingers 88 each time the pusher plunger 30 is moved rearwardly during a retraction of the pusher.

Each rearward movement of the arm 101 serves to store energy in a spring 102 which is mounted within the casing 99 and return movement of the arm 101 urged by the spring 102 is controlled by an escapement mechanism 103 mounted within the casing. Thus each rearward movement of the arm 101 occasioned by retraction of the pusher plunger 30 is rapid, but return or forward movement of the arm is very slow under the control of the escapement mechanism 103.

A timer switch 104 is supported by the shaft 95 and this switch is of the well known type in which the circuit controlling contacts are normally spaced apart or open. The switch contacts are caused to engage to complete a circuit through the switch only when the switch plunger 105 is pushed inwardly. In order to accomplish this a disk 106 is secured to rotate with the rotor 100 and is provided at one point on its periphery with an actuator hump or cam portion 107 which is engageable with a roller 108 carried at the free end of a yieldable arm 109 which overlies the plunger 105 and is secured to the switch as at 110.

After each crank arm 101 is moved rearwardly a definite distance by retraction of the pusher plunger 30 it starts to return slowly to its initial forward position by action of the spring 102 and under control of the escapement mechanism 103. After it has returned a predetermined distance, determined by placement of the shaft 95 and the switch 104 movable therewith, the hump 107 on the disk 106 will engage the roller 108 and cause the arm 109 to force the plunger inwardly and close the control circuit through the switch 104. It is to be understood, however, that the circuit closed through the respective switch 104 will be effective to initiate another cycle of movement of the crank shaft 71 and thereby effect a

retraction and an advancement of the pusher 24 and an attendant advancement and retraction of the fuel feeding slide 43 only when the positioning switches are closed. These positioning switches will be described hereinafter and it is to be understood that they are closed only when the pusher is in its most advanced position and the fuel feeding slide in its fully retracted position.

While it is preferred that the pusher plate 24 always be stopped in its most advanced position, and the fuel feeding slide in its fully retracted position, it is to be understood that the parts can be so timed as to stop the pusher plate and the slide in any predetermined relation. Should the parts be timed so that the pusher plate 24 can come to rest in a retracted or partially retracted position, the feature of providing primary air intake ports 15 in the bottom of the fire pot and pusher tunnel only in advance of or forwardly of the most advanced position of the pusher plate 24 effectively overcomes the possibility of any fresh coal which might be disposed in front of the retracted pusher plate receiving enough oxygen to burn and fuse or stick to the tunnel floor and by this means jam or tend to jam the next forward movement of the pusher plate.

Two additional or auxiliary control switches generally designated 111 are provided and each is mounted for being automatically actuated by movement of the ash discharging door. One such switch is mounted at each side of the ash discharging door as shown in Figures 6 and 7. These switches are so formed and connected in the control circuits later to be described that they dominate the control and permit continuous reciprocations of the pusher 24 and the fuel feeding slide 43 when a fresh fire is being built and before a fuel mass has been advanced over the fire pot bottom and into contact with the ash discharging door, and also at times when very rapid combustion provides an excess of ash and clinker formation which when discharged through the ash door provides a temporary void or a minimum of fuel mass congestion resulting in a complete closure of the ash discharge door 18.

The particular switch structure illustrated herein, particularly in Figures 6 and 7 of the drawings, are of the same type illustrated at 104 in Figure 13 and each includes a casing 112 which is attached, as at 113, to one of the side plates 62 and a contact making and breaking plunger 114 reciprocable in and extended from the casing. Each plunger is engageable by an actuator 115 fixed to the ash door at the respective side so as to be moved to its circuit completing position each time the door moves about its pivotal mounting 19 to its fully closed position. It is to be understood that whenever the ash discharge door is in the closed position illustrated in Figure 7 of the drawings, the switches generally designated 111 dominate the control of the furnace and cause the crank shaft 71 to rotate continuously. It will be obvious that if rotation is imparted to this crank shaft at the rate of one revolution every two minutes, thirty reciprocations will be imparted during an hour to the pusher 24 and the fuel feeding slide 43 under control domination of the switch 111. Whenever the feeding and advancement of fuel brings about a sufficient fuel mass congestion in the fire pot 10, the ash discharge door 18 will be forced open an amount sufficient to cause the switch plungers 114 to break the dominant con-

control circuits through the switches 111 and restore the fast and slow timer units to normal control of the furnace operation.

The position switch equipments will now be described. An actuator cam 116 is mounted upon the crank shaft 71, and this cam is provided with two diametrically oppositely disposed peripheral recesses 117, each said recess being positioned in a distinct vertical plane traversing the axis of the crank shaft. The cam is adjustably secured upon the crank shaft by a set screw 118. It is preferred that the recesses 117 be so disposed as to assure stoppage of the pusher 24 and the fuel feeding slide 43 respectively in the fully advanced and fully retracted positions, but it is to be understood that by reason of the adjustable mounting of the cam, stoppage of the parts can be effected with the elements 24 and 43 in any predetermined positions.

A position switch 119 is associated with the fast timer, and a position switch 120 is associated with the slow timer. Each of these switches is of the well known, normally open or contact spaced type, the contacts being caused to engage only when the switch plunger 121 is forced inwardly. Each switch is equipped with an actuator roller 122 supported at the free end of a yieldable arm 123 overlying the respective plunger 121 and secured, as at 124, to the switch body. The rollers ride upon the peripheral surface of the cam 116 and are receivable in the recesses 117 previously referred to.

Circuits through the switches 119 and 120 are completed at all times except when the rollers drop into the recesses 117 and thereby permit the plunger to move outwardly and permit separation of the switch contacts. As will be later described, these position switches 119 and 120 are so connected in the control circuits in cooperative relation with the timing switches 89 and 90 that each control circuit will be initiated by the respective timing switch 89 or 90, and once movement of the crank shaft and resultant movement of the pusher 24 and the fuel feeding slide 43 is initiated it will be continued by operation of the respective position switch until these elements have moved through a complete cycle and have been returned to the starting position, at which time the rollers 122 will drop into the recesses 117 and effect a breaking of the motor circuit.

In Figures 8 and 9 of the drawings, there is illustrated a modified form of the invention in which the dome 125 and the arch 126 are formed of metal. In this modified arrangement the arch 126 is equipped with a seat 127 at its lower edge for removably receiving a fire brick arch 128. Like the arch previously described, this arch 128 is closely spaced above the fire pot so as to provide a restricted space 129 for passage of gases and smoke close to the underlying incandescent fire bed. The arch 128 is provided with a transverse secondary air groove or channel 130 which is supplied with secondary air at one or both ends through an end duct or ducts 131 preferably provided with adjustable plate valve equipment 132.

In Figure 16 of the drawings the electrical control connections of the various control devices for use in a furnace adapted for the burning of solid fuel other than anthracite are shown. In this illustration the positive power line is indicated at 133 and the negative line at 134. The positive line is connected at 135 with the pusher and slide actuating motor 73 through the fast timer unit 89, and this line is connected, as at

136, with said motor through the position switch 119. The negative line 134 is connected with the motor 73, as at 137, through the slow timer unit 90, and this negative line is likewise connected, as at 138, with said motor through the position switch 120. The fan diagrammatically illustrated at 60-61 and which serves to supply the primary and secondary air is connected, as at 139, with the connections 137 and 138 leading to the motor 73, and this fan is also connected, as at 140, with the positive power line 133. A thermostat T is shown as connected as at 141 as a by-pass around the slow timer 90.

Figure 17 is a view similar to Figure 16 but diagrammatically illustrates the control parts as connected for use in a furnace adapted for the burning of anthracite coal. In this illustration the thermostat may be of the form well known and including two simultaneously operable mercury switches diagrammatically illustrated at T¹ and T². This thermostat is connected, as at 142, as a by-pass around the slow timer 90, and an additional fan control timer 143 is connected as at 144, directly between the motor and fan assembly 60-61 and the negative power line 134. In all other respects this control circuit is identical with the illustration in Figure 16 and is so designated. When anthracite coal is being burned in the furnace, it is desirable that the additional fan control timer 143 be included so as to enable the motor and fan assembly 60-61 to operate for short periods while the furnace is idling and independently of the operation of the stoker motor 73.

If desired, the ash discharge gate operated switches generally designated 111 may be omitted, and in such cases the electrical connections with the various control devices can be made as illustrated in Figures 16 and 17. When the ash discharge door operated switches 111 are included, they may be electrically connected in the control circuits in the manner illustrated in Figure 18. Figure 18 is a view similar to Figure 16 and like electrical connections therein are designated in like manner as indicated. In this figure, one of the ash discharge door operated switches 111 is shown as connected at 145 between the positive power line 133 and the stoker motor 73 so as to dominate the position switch 119 and the fast timer unit 89, and the other of these switches 111 is similarly connected, as at 146, between the negative power line 134 and the stoker motor 73 so as to dominate the position switch 120 and the slow timer unit 90. With the switches 111 thus connected in the control circuit, it will be obvious that whenever the ash discharge door 18 is closed the stoker motor 73, and also the fan and fan motor 60-61, will be caused to operate continuously independently of the timer units 89-90, the position switches 119-120, and also the thermostat T. In order to avoid operation of the stoker motor and the fan motor when the ash discharge door is closed and it is desired that the furnace should remain out of operation, a manually operable circuit breaking switch 147 may be employed.

It will be apparent that the thermostat serves to effect a selection between the fast and slow fuel feed timing controls. When the thermostat 70 is closed by a heat demand, the current reaches the stoker motor through the fast timing control equipment. The slow timing control equipment is not intended to function when the fast timing equipment is in control of the stoker motor operation. Therefore, as long as the thermostat by-

passes the current about the slow timing control equipment the fast timing control equipment will remain in complete control, assuming, of course, that the circuit through the ash discharge door operated switches 111 is broken. When such switches are in use in the system, these switches being in dominant control whenever said door is closed as hereinbefore described. The position of the controlling thermostat is determined by the purpose for which the heating unit is being used. If the unit is being used for hot water heating, the thermostat will be located so as to cut in whenever the temperature in the hot water tank has fallen below a predetermined point, and to cut off when said temperature has risen above a predetermined point. When the heating unit is being employed as a part of a hot water heating system in a house or apartment, the thermostat would be located centrally in the house or apartment and would function in the same manner just above described with the exception that the medium controlling the function of the thermostat would in this case be air instead of water as in the previously mentioned case. In other words, whenever the temperature in the house or apartment rose above the predetermined point it would cut the furnace off, and when it fell below the predetermined point it would serve to cut the furnace on. However, in the hot air installation, the thermostat would indirectly control the furnace operation and would be supplemented by a thermostat installation known as a bonnet control. The main thermostat in the house or apartment would control the air circulating fan hereinbefore referred to, which would act to raise or lower the bonnet temperature in the furnace, and as the bonnet temperature was raised or lowered the bonnet control thermostat would control the actual stoker mechanism to keep the bonnet temperature between predetermined limits. This method of bonnet control is well known and need not be additionally dwelt upon.

Should the heating unit be employed in connection with a steam or hot water system, the thermostat would again operate directly on the stoker to keep the steam or hot water within the predetermined temperature limit. It will be apparent also that when a steam system is employed, it may be found desirable to control it with pressure as the factor instead of temperature, in which case the system would include a pressurestat instead of a thermostat.

In the practical operation of the furnace, access may be had to the fire pot through the side door 70 and a fire may be laid therein in the normal way by the common expedient of laying paper and kindling upon the supporting bottom 13 and igniting the same, and thereafter supplying solid fuel so as to obtain a substantial fire. After a substantial fire has been obtained, the mechanical controls can be resorted to. By closing the manual switch 147, the ash discharge door operated switches 111 will be placed in control and will cause the stoker motor 73 and the fan-motor combination 60-61 to operate continuously until a sufficient amount of fuel has been fed into the fire pot, in successive stages, to engage and force open the ash discharge door 18, at which time the circuit through the switches 111 will be broken and the normal timing controls will take over the controlling function. Obviously, if there is no heat demand upon the thermostat T at this time, the idling or slow feed control equipments will become effective. Should the thermostat T be closed however, indicating a demand for heat, the

fast timing equipment will be selected to control the operation of the furnace and the fuel feeding slide 43 and the fuel bed advancing pusher 24 will be reciprocated the predetermined number of times per hour controlled by this timing equipment until the heat demand is satisfied, at which time the thermostat T will open and the slow timing equipment will be placed in control and it will function to supply just enough fuel to maintain the fire in an idling condition regardless of the length of the period preceding the next heat demand.

Once normal operation of the fire has been achieved, the fast and slow timing equipments alone normally function to control operation of the furnace, and it has been found that approximately one-tenth of the volume of the fuel fed is expelled from the ash discharge door when the fuel being used is ordinary bituminous coal. This 15 expelled volume is pure ashes. Should a period of very rapid combustion result in an abnormal burning of fuel and the formation of a clinker of considerable size, then, and then only, will the ash discharge door operated switches 111 function. As a clinker thus formed falls from the ash discharge door, it creates a considerable void in the fire pot and permits the ash discharge door to close. The closing of this door closes the control circuits through the switches 111 and causes them to dominate the furnace control as in the case of the starting of the fire hereinbefore described, and the fuel feeding slide 43 and the pusher 24 and the fan would be caused to operate continuously until the void is filled and a fuel bed 20 congestion established sufficient to force open the ash discharge door 18 and break the circuit through the switches 111, thereby to return the control of the furnace operation to the normally functioning fast and slow timer equipments.

Assuming that the thermostat T is closed, indicating a demand for heat, and thus selecting the fast timing equipment as the furnace stoking control, current will pass from the positive line 133 through the fast timer unit 89 (when 25 closed) to the motor 73 and back through the thermostat T to the negative line 134, thus initiating an operation of the motor to bring about one complete cycle of operation of the fuel feeding slide 43 and the pusher 24, namely, a retraction of the pusher accompanied by a fuel feeding advancement of the slide, and a retraction of the slide accompanied by an advancement of the pusher to its initial position. As the pusher plunger 30 moves rearwardly, the 30 fingers 88 projecting laterally therefrom will reset the two timing switches, breaking the circuits therethrough and restoring energy in the springs 102 as hereinbefore described. Before the circuit is thus broken through the timing switch 89, initiation of movement of the crank 35 shaft 71 will effect a completion of the circuit through the position switch 119 so that the circuit once completed will be maintained in the completed state by the position switch until the complete reciprocation cycle is effected and the slide and pusher are returned to their initial positions illustrated in Figure 1. It will be noted that during the fast timer controlled operation of the furnace the circuit through the motor and fan assembly 60-61 is maintained through the thermostat T so that the fan operates continuously so long as there is a heat demand.

When the heat demand is satisfied, the circuit through the thermostat T is broken and the slow timing equipment is rendered effective to

control the operation of the furnace. As previously stated, this slow timing equipment functions identically with the fast timing equipment in that it serves to impart a definite number of fuel feeding and fuel bed advancing reciprocations to the slide 43 and the pusher 24 in a given time interval, but during this control the number of such reciprocations is much less than the number of reciprocations when the fast timing equipment is in control. It will be apparent that when the slow timing equipment is dominating the furnace control, the fan and motor assembly controlling circuit is completed through the position switch 120 rather than the thermostat T, and therefore the fan will operate intermittently only, or, in other words, only when the stoker motor 73 is operating. In Figure 17 of the drawings, however, there is illustrated a modified control circuit in which is included an additional timer 143 which may be employed when anthracite coal is being burned to cause the fan to operate at intervals during the idling operation of the furnace so that air will be supplied to the combustion chamber at intervals independently of the operation of the stoker motor.

By reason of the provision of the two fuel feed rates and the two air supply rates, one for maximum combustion and one for idling, it is possible to properly adjust the combustion rate for these two conditions and keep the fire pot in practically uniform condition with only fine ash being discharged through the ash discharge door 16. With the equipment herein illustrated and described, it has been found possible to hold the fire indefinitely while idling and at the same time have the fire bed ready to go full tilt in a few moments after the full air supply and fast timing rates go into effect.

The improved furnace structure herein disclosed can be readily conditioned for the use of any of various types of fuel. This may be done by merely adjusting the ash discharge door weight 20 and/or by adjusting the feed rate per hour of the new fuel charges and/or by adjusting the air supply. The feed rate per hour is adjustable either by adjusting the stroke of the feed slide 43 in the manner hereinbefore described, or by the readily accessible and simple adjustment of the timing devices illustrated in Figures 11 to 13 of the drawings whereby the number of fuel feed strokes per hour is controlled. The same furnace can be used for any size of bituminous or anthracite coal within its range, and can be adjusted quickly for low fusing point coal ash as well as high.

In the operation of the furnace, the rate of feed at high capacity, for most economical operation, should never exceed the combustion capacity of the fire pot for the type of fuel being used and for the depth of the fuel bed that is provided. Otherwise, there will be a discharge of unburned fuel into the ash pit. Furthermore, the conditions in the combustion chamber should remain practically uniform so that the air supply can be scientifically adjusted to avoid loss of heating unused oxygen. Thirdly, the intensity of the air blast should not be such as to convert the ashes into clinkers. Fourthly, to prevent all clinker formation the fuel should not be converted into ash until just before it is discharged from the combustion chamber. In the use of the improved stoking equipment herein disclosed, it is possible to obtain these advantages in the operation of the furnace. There

can be obtained a condition of economical equilibrium between fuel supply and combustion rate, which is automatically maintained and which will provide a fire pot for a burning fuel that becomes ashes only when it has come close to the point of discharge at the end of the fire pot. The simple adjustments and automatic operations already referred to accomplish these ends.

For any rate of feed which is less than the 10 combustion capacity of the furnace, the fire pot will automatically condition itself to certain accumulation of ashes at the discharge end of the fire pot. To the extent that these ashes thus collect, there is a reduction in the combustion area on the fire pot bottom, and this reduction in the effective fire pot bottom or grate area causes automatically a similar reduction in the combustion capacity of the fire pot which automatically equalizes the combustion rate with the rate of feed of fuel. An equilibrium will thus be attained regardless of the adjustment of the feed therein. Due to the attainment of this equilibrium, if the stoker is adjusted so that it is underfed or over-aired, the fire will not go out. There will always be a portion of the fire pot which is burning effectively. The only effect of underfeeding will be that of cutting down the heat capacity of the furnace. The combustion will still be reasonably efficient and of the desired character. The ideal condition will be that adjustment which gives the minimum amount of undischarged ash at the end of the fire pot where the least amount of air is passing through the ashes and not doing its bit in consuming unburned fuel. Air passing through ashes into the combustion chamber represents waste to the extent that it is not used in completing combustion of gases reaching this end of the combustion chamber.

30 40 The particular arrangement of the dome 38 and the arch 39, and the provision of the restricted passage 40 directly over the incandescent portion of the fire bed makes it possible to operate the herein disclosed furnace in approximately smokeless fashion. The successively supplied fresh charges of fuel fall into the space provided by retraction of the pusher 24 at the rear end of the fire pot. These charges are relatively small and the volatiles and smoke which pass off therefrom move forwardly in their course toward the flue 37 and are caused to intimately contact with the incandescent fuel bed portion beneath the restricted outlet 40 so as to be consumed. The incandescent portion of the fuel bed supplies the necessary heat, and the arch ports 69 the necessary oxygen to provide for the desired combustion of these gases.

50 55 60 65 70 It has been discovered that even without the use of the baffle wall 39 and without the use of a secondary air supply, bituminous high volatile coal burns with extremely little smoke due to the fact that the small quantity of volatile matter discharged from each of the small supplies fed at a time will be consumed in the general combustion of the large combustion chamber before the next following fresh fuel supply is fed. Surplus oxygen passing through the fuel bed, or ashes in the fire pot, aids in accomplishing this purpose.

75 It will be apparent that the primary air introduced into the fire pot is preheated by drawing the heat away from the side walls of the fire pot. The heat thus taken off from the side walls is not lost, however, because it is added to the air

which goes into the fire pot, and it has been found that much more efficient combustion is attained by introducing the primary air in the particular manner herein disclosed. The secondary air also is preheated during its passage through the arch 39 directly over the fire bed.

The furnace structure herein disclosed will be found very advantageous and efficient. In it provision is made for discharging ash and clinkers without auxiliary mechanism, very few working parts are included and the parts which are included, other than the electric motors and motor gear reductions, on account of the slowness of their movements, will operate in a substantially noiseless manner and present no lubrication problems. Very little power consumption is necessary, and the furnace can operate at a materially reduced repair and power cost for a given output of heat. A motor of $\frac{1}{30}$ of a horse-power will satisfactorily handle all operations except that of the fan for a furnace having a consumption capacity of 25 pounds of bituminous coal per hour. A positive feed cycle is provided. Set timings operate this feed cycle for both high capacity and for idling at an invariable rate for an approximately invariable amount of feed per hour. There are, however, combined with the preliminary setting of the feed rates for high capacity and idling, the automatic features referred to which provide uniform conditions in the fire pot at both extremes of the combustion rate. The conditions inside the fire pot will come to an equilibrium according to the way the controls are set, and the setting of these controls thereafter automatically regulates the available amount of combustion in the fire pot and the nature of discharge from the discharge end of the fire pot according to the pleasure of the operator.

In our improved furnace, means is provided for effecting an automatic delivery of the ashes through the discharge end of the fire pot. In the operation of the furnace, there is no extensive accumulation of ashes except at the discharge end of the fire pot, and in this way a practically uniform condition of the combustion zone is maintained at all times so that the air supply can be perfectly adjusted to the fuel supply and so that there will be no excess of air provided. By checking the analysis of the stack gases, it is possible to determine whether or not too large a quantity of air is being supplied for the amount of fuel being fed, et cetera. By reason of the provision of the equipment herein shown and described, a scientific adjustment can be effected which will be perfect as long as this adjustment is maintained and the same type of fuel is used, and when the type of fuel is changed the necessary re-adjustment can be readily and easily effected. The uniform fire pot conditions which are in equilibrium with the air supply pertain whether the stoker is running at full capacity or idling. There will be no intermediate periods of conditions during which the high capacity of the combustion experiences any appreciable variations.

The provision of the downwardly sloping bottom in the fire pot renders possible the use of a relatively long fire pot and the provision of a large grate area for a certain width of fire pot without increasing the depth of the fire bed unduly. By controlling the downward slope of the bottom of the fire pot where the fire pot is relatively long, it is possible to yieldably close the discharge gate 18 and obtain effective control by

its use and at the same time keep down the depth of the fuel bed to a reasonable point.

It is of course to be understood that the details of structure and arrangement of parts may be variously changed and modified without departing from the spirit and scope of the invention as pointed out in the appended claims.

We claim:

1. In a furnace, a longitudinal fire pot having a receiving end and an end portion over which ash and clinker can be discharged and including a fuel mass supporting bottom and fuel mass retaining side walls, a pusher reciprocably mounted at the fresh fuel receiving end of the fire pot remote from said discharge end for advancing fresh fuel charges and fuel mass along the fire pot, a fresh fuel hopper having a discharge throat disposed above and adjacent said receiving end, a fresh fuel charge pushing slide reciprocable at least part way across said throat for feeding successive charges of fuel into the space formed by each retraction of the pusher, driving means for said pusher and slide, and control means for automatically controlling operation of said driving means responsive to heat demands and including devices for causing the pusher and slide always to stop in a predetermined position.
2. In a furnace, a longitudinal fire pot having a receiving end and an end portion over which ash and clinker can be discharged and including a fuel mass supporting bottom and fuel mass retaining side walls, a pusher reciprocably mounted at the fresh fuel receiving end of the fire pot remote from said discharge end for advancing fresh fuel charges and fuel mass along the fire pot, a fresh fuel hopper having a discharge throat disposed above and adjacent said receiving end, a fresh fuel charge pushing slide reciprocable at least part way across said throat for feeding successive charges of fuel into the space formed by each retraction of the pusher, driving means for said pusher and slide, and selective control means responsive to heat demands for controlling operation of said driving means for feeding a predetermined definite number of fuel charges into the fire pot in a given interval of time and in advance of the pusher to be pushed along the bottom thereby for maximum combustion operation of the furnace, or for similarly feeding a predetermined definite lesser number of fuel charges into the fire pot in the same given interval of time for idling operation of the furnace.
3. In a furnace, a longitudinal fire pot having a receiving end and an end portion over which ash and clinker can be discharged and including a fuel mass supporting bottom and fuel mass retaining side walls, a pusher reciprocably mounted at the fresh fuel receiving end of the fire pot remote from said discharge end for advancing fresh fuel charges and fuel mass along the fire pot, a fresh fuel hopper having a discharge throat disposed above and adjacent said receiving end, a fresh fuel charge pushing slide reciprocable at least part way across said throat for feeding successive charges of fuel into the space formed by each retraction of the pusher, driving means for said pusher and slide, selective control means responsive to heat demands for controlling operation of said driving means for feeding a predetermined definite number of fuel charges into the fire pot in a given interval of time and in advance of the pusher to be pushed along the bottom thereby for maximum combustion operation of the furnace, or for similarly feeding a predetermined definite lesser number of fuel charges

into the fire pot in the same given interval of time for idling operation of the furnace, means for varying the amount of fuel comprising each fuel charge, a swingably mounted gate for yieldably resisting passage of ash and clinkers through the discharge end of the fire pot, and adjustable means for setting up a variable resistance to opening of said gate.

4. In a furnace, a longitudinal fire pot having a receiving end and an end portion over which ash and clinker can be discharged and including a fuel mass supporting bottom and fuel mass retaining side walls, a pusher reciprocably mounted at the fresh fuel receiving end of the fire pot remote from said discharge end for advancing fresh fuel charges and fuel mass along the fire pot, a fresh fuel hopper having a discharge throat disposed above and adjacent said receiving end, a fresh fuel charge pushing slide reciprocable at least part way across said throat for feeding successive charges of fuel into the space formed by each retraction of the pusher, driving means for said pusher and slide, selective control means responsive to heat demands for controlling operation of said driving means for feeding a predetermined definite number of fuel charges into the fire pot in a given interval of time and in advance of the pusher to be pushed along the bottom thereby for maximum combustion operation of the furnace, or for similarly feeding a predetermined definite lesser number of fuel charges into the fire pot in the same given interval of time for idling operation of the furnace, a swingably mounted gate for yieldably resisting passage of ash and clinkers through the discharge end of the fire pot, and additional control means effective whenever said gate is fully closed to dominate the other controls and cause the driving means to operate continuously to feed successive charges of fuel until the gate is opened a predetermined amount by ash or clinker accumulation discharge therethrough.

5. In a furnace, a longitudinal fire pot having a receiving end and an end portion over which ash and clinker can be discharged and including a fuel mass supporting bottom and fuel mass retaining side walls, a pusher reciprocably mounted at the fresh fuel receiving end of the fire pot remote from said discharge end for advancing fresh fuel charges and fuel mass along the fire pot, a fresh fuel hopper having a discharge throat disposed above and adjacent said receiving end, a fresh fuel charge pushing slide reciprocable at least part way across said throat for feeding successive charges of fuel into the space formed by each retraction of the pusher, and means for moving the pusher and slide in timed relation, said last named means including a rotary crank shaft and driving connections between the crank shaft and said pusher and slide and control devices for causing the crank shaft to turn in identical individual successive cycles thereby to always leave the pusher and slide in the same position following completion of each cycle.

6. In a furnace, a longitudinal fire pot having a receiving end and an end portion over which ash and clinker can be discharged and including a fuel mass supporting bottom and fuel mass retaining side walls, a pusher reciprocably mounted at the fresh fuel receiving end of the fire pot remote from said discharge end for advancing fresh fuel charges and fuel mass along the fire pot, a fresh fuel hopper having a discharge throat disposed above and adjacent said receiving end, a fresh fuel charge pushing slide reciprocable at

least part way across said throat for feeding successive charges of fuel into the space formed by each retraction of the pusher, driving means for said pusher and slide, selective control means responsive to heat demands for controlling operation of said driving means for feeding a predetermined definite number of fuel charges into the fire pot in a given interval of time and in advance of the pusher to be pushed along the bottom thereby for maximum combustion operation of the furnace, or for similarly feeding a predetermined definite lesser number of fuel charges into the fire pot in the same given interval of time for idling operation of the furnace, and means including a fan for supplying air for combustion to the fire pot continuously during maximum combustion operation of the furnace and intermittently during idling operation of the furnace.

7. In a furnace, the combination of a longitudinal fire pot having a receiving end and an end portion over which ash and clinker can be pushed and discharged and also having a fuel mass supporting bottom and fuel mass retaining side walls, a reservoir for solid fuel supported beyond said receiving end and having a discharge throat located higher than the normal level of burning fuel in the fire pot, a fuel mass pusher reciprocable in the direction of the length of the fire pot with its face serving at least in part as a rear closure for said pot and bearing constant upright angular relation to said bottom and effective when moved forwardly to push fuel mass before it over said bottom and when retracted to provide a fresh fuel receiving pocket between said face and said fuel mass, a feed plunger reciprocable at least part way across said throat in a path substantially paralleling the path of movement of the pusher and above said level of burning fuel for feeding fuel from said throat to fall by gravity into said pocket, means operable during maximum heat demands for continuously reciprocating and timing said pusher and feed plunger so that the latter moves forwardly when the former is retracted, means for varying the stroke of the feed plunger to vary the amount of fuel forced to fall into said pocket on each forward movement thereof, baffle means disposed forwardly of the feed plunger and shielding fuel in the throat and reservoir from heat in the pot, and means for continuously and regulatably introducing air into the fire pot to support combustion therein.

8. A furnace structure as defined in claim 7 in which there is included a gate having flexible fingers disposed across the reservoir throat to retain fuel therein when the feeder plunger is being retracted and through which fuel charges can be forced by the feed plunger to fall by gravity into the fire pot, and which can flex to conform about fuel lumps and prevent sifting through of fine fuel from said throat at the sides of said lumps.

9. A furnace structure as defined in claim 7 in which the pusher and the feeder plunger are so constructed and cooperatively arranged that the pocket formed by retraction of said pusher always is larger than the volume of a fuel charge fed by forward movement of the feed plunger so that successively fed charges of fresh fuel do not increase the depth of the main fuel bed in the fire pot.

10. A furnace structure as defined in claim 7 in which the feed plunger stroke adjusting means

comprises adjustable lost motion connections in the continuously operating reciprocating and timing means.

11. A furnace structure as defined in claim 7 in which the fire pot bottom has apertures which are hooded in the direction toward the discharge end and through which the combustion supporting air is directed, thereby to prevent free falling of ash through said apertures and causing substantially all ashes or solid products of combustion to be discharged over said discharge end.

12. A furnace structure as defined in claim 7 in which the fire pot bottom has apertures therein and the combustion supporting air is directed to said apertures from an exhaust fan and through guiding means.

13. A furnace structure as defined in claim 7 in which the fuel mass engaging pusher face of the pusher is of greater area than the fuel engaging pusher face of the feed plunger.

14. A furnace structure as defined in claim 7 in which the center of the fuel engaging pusher face of the pusher lies substantially in the same vertical longitudinal plane as the center of the fuel engaging face of the feed plunger.

15. A furnace structure as defined in claim 7 in which the pusher and the feed plunger are reciprocated synchronously by a single source of mechanical power.

16. A furnace structure as defined in claim 7 in which there is provided a throat floor over which the feed plunger moves and in which the pusher has a generally horizontal top portion, said floor being spaced above the pusher top portion by a member contacted by air from outside the furnace thereby to retain a relatively cool condition of said member and insulate the fuel engaging face of the feed plunger from the heat of the pusher.

17. A furnace structure as defined in claim 7 in which the pusher has a generally horizontal top portion, and in which the throat shielding baffle means includes an element portion reaching down approximately to the level of said pusher top portion.

18. A furnace structure as defined in claim 7 in which there is provided a throat floor over which the feed plunger moves and in which the throat shielding baffle means includes a swingably mounted gate suspended over said floor with its lower free edge portion disposed adjacent said floor.

19. A furnace structure as defined in claim 7 in which there is included means for yieldably resisting ash discharge from the discharge end portion of the fire pot bottom, and means for varying the amount of said resistance.

20. In a furnace, a longitudinal fire pot having a receiving end and an end portion over which ash and clinker can be discharged and including a fuel mass supporting bottom and fuel mass retaining side walls, means for moving fresh fuel charges and fuel mass along said bottom toward said discharge end, said side walls having primary air openings therethrough and extending along the fire pot just above said bottom, said bottom having openings therethrough, casing structure so constructed and arranged as to form a primary air delivery chamber disposed beneath the bottom for directing primary air upwardly therethrough and extending upwardly laterally of said side wall portions into position for communicating with said side wall openings to direct said air into the side wall openings.

21. In a furnace, a longitudinal fire pot having

a receiving end and an end portion over which ash and clinker can be discharged and including a fuel mass supporting bottom and fuel mass retaining side walls, means for moving fresh fuel charges and fuel mass along said bottom toward said discharge end, said side walls having primary air openings therethrough and extending along the fire pot just above said bottom, said bottom having openings therethrough, casing structure so constructed and arranged as to form a primary air delivery chamber disposed beneath the bottom for directing primary air upwardly therethrough and extending upwardly laterally of said side wall portions and then downwardly parallel and against said side wall portions into position for communicating with said side wall openings to project a sheet of air in preheating contact with each said side wall portion prior to entry through the side wall openings into the fire bed on the fuel mass supporting bottom.

22. In a furnace, a longitudinal fire pot having a receiving end and an end over which ash and clinker can be discharged and including a fuel mass supporting bottom and fuel mass retaining side walls, a pusher reciprocably mounted at the receiving end of the fire pot remote from said discharge end for feeding fuel mass along the fire pot, a fresh fuel hopper having a discharge throat, means supporting said hopper with its discharge throat disposed above and adjacent said receiving end, a fresh fuel charge pushing slide reciprocable at least part way across said throat for feeding successive charges of fuel from said throat to fall by gravity into the space formed by each retraction of the pusher, a yieldable gate, means for supporting said gate across said throat in position for being normally effective to hold fuel in the throat, said gate including a plurality of depending closely related spring fingers yieldable to permit passage of fuel being pushed by said slide, and means for moving the pusher and the slide in timed relation.

23. In a furnace, the combination defined in claim 22 in which is included a flap swingably mounted between the yieldable gate and the fire pot for shielding fuel in the hopper from radiant heat from the fire pot.

24. In a furnace, a longitudinal fire pot having a receiving end and an end over which ash and clinker can be discharged and including a fuel mass supporting bottom and fuel mass retaining side walls, a pusher reciprocably mounted at the receiving end of the fire pot remote from said discharge end for feeding fuel mass along the fire pot, a fresh fuel hopper having a discharge throat, means supporting said hopper with its discharge throat disposed above and adjacent said receiving end, a fresh fuel charge pushing slide reciprocable at least part way across said throat for feeding successive charges of fuel from said throat to fall by gravity into the space formed by each retraction of the pusher, a yieldable gate, means for supporting said gate across said throat in position for being normally effective to hold fuel in the throat, said gate including a plurality of depending closely related spring fingers yieldable to permit passage of fuel being pushed by said slide, and means for moving the pusher and the slide in timed relation, said last named means including a rotary crank shaft having two cranks thereon, a lever pivoted at one end and connected at its other end with the slide, a lever pivoted at one end and connected at its other end

with the pusher, and links connecting said levers with the cranks on the crank shaft.

25. In a furnace, a longitudinal fire pot having a receiving end and an end over which ash and clinker can be discharged and including a fuel mass supporting bottom and fuel mass retaining side walls, a pusher reciprocably mounted at the receiving end of the fire pot remote from said discharge end for feeding fuel mass along the fire pot, a fresh fuel hopper having a discharge throat, means supporting said hopper with its discharge throat disposed above and adjacent said receiving end, a fresh fuel charge pushing slide reciprocable at least part way across said throat for feeding successive charges of fuel from said throat to fall by gravity into the space formed by each retraction of the pusher, a yieldable gate, means for supporting said gate across said throat in position for being normally effective to hold fuel in the throat, said gate including a plurality of depending closely related spring fingers yieldable to permit passage of fuel being pushed by said slide, and means for moving the pusher and the slide in timed relation, said last named means including a rotary crank shaft having two cranks thereon, a lever pivoted at one end and connected at its other end with the slide, a lever pivoted at one end and connected at its other end with the pusher, links connecting said levers with the cranks on the crank shaft, and means for adjustably connecting at least one of said links with the associated lever for enabling adjustments of the degree of relative movement imparted to said levers.

26. In a furnace, a longitudinal fire pot having a receiving end and an end over which ash and clinker can be discharged and including a fuel mass supporting bottom and fuel mass retaining side walls, a pusher reciprocably mounted at the receiving end of the fire pot remote from said discharge end for feeding fuel mass along the fire pot, a fresh fuel hopper having a discharge throat, means supporting said hopper with its discharge throat disposed above and adjacent said receiving end, a fresh fuel charge pushing slide reciprocable at least part way across said throat for feeding successive charges of fuel from said throat to fall by gravity into the space formed by each retraction of the pusher, a yieldable gate, means for supporting said gate across said throat in position for being normally effective to hold fuel in the throat, said gate including a plurality of depending closely related spring fingers yieldable to permit passage of fuel being pushed by said slide, and means for moving the pusher and the slide in timed relation, said last named means including a rotary crank shaft having two cranks thereon, a lever pivoted at one end and connected at its other end with the slide, a lever pivoted at one end and connected at its other end with the pusher, and links connecting said levers with the cranks on the crank shaft, said cranks being extended diametrically oppositely from said crank shaft thereby to cause the pusher and slide to move in opposite directions.

27. In a furnace, a fire pot, fuel feeding means for feeding fuel charges into the fire pot, driving means for said fuel feeding means, a first controlling means for the driving means operable to render the fuel feeding means effective for feeding a predetermined definite number of fuel charges into the fire pot in a given interval of time for maximum combustion operation of the furnace, a second controlling means for the

driving means operable to render the fuel feeding means effective for feeding a predetermined definite lesser number of fuel charges into the fire pot in the same given interval of time for idling operation of the furnace, means automatically responsive to heat demands during normal operation for rendering said first and second driving means controlling means selectively effective, and a third controlling means for the driving means operable as a result of abnormally rapid combustion in the fire pot or incidental to initial making up of a fire in said fire pot to dominate all controls and cause said driving means to render the fuel feeding means effective for feeding successive fuel charges continuously until normal combustion conditions are reestablished.

28. In a furnace, a fire pot, fuel feeding means for feeding fuel charges into the fire pot, driving means for said fuel feeding means, a first controlling means for the driving means operable to render the fuel feeding means effective for feeding a predetermined definite number of fuel charges into the fire pot in a given interval of time for maximum combustion operation of the furnace, a second controlling means for the driving means operable to render the fuel feeding means effective for feeding a predetermined definite lesser number of fuel charges into the fire pot in the same given interval of time for idling operation of the furnace, means automatically responsive to heat demands during normal operation for rendering said first and second driving means controlling means selectively effective, and a third controlling means for the driving means operable as a result of abnormally rapid combustion in the fire pot or incidental to initial making up of a fire in said fire pot to dominate all controls and cause said driving means to render the fuel feeding means effective for feeding successive fuel charges continuously until normal combustion conditions are reestablished and then automatically restore the selective control of said first two mentioned selectively effective driving means controlling means.

29. In a furnace structure, a fire pot, a feedway having a discharge end, a reciprocating slide for forcing the fuel charges along and off the discharge end of said feedway, means supporting said feedway in position for having fuel forced off the discharge end thereof fall by gravity into the fire pot, a gate structure, and means supporting the gate structure across said feedway in position for normally obstructing fuel passage in the feedway, said gate including a plurality of closely arranged spring fingers yieldable to pass fuel charges either including or devoid of lumps or units of foreign matter as they are forced along by each forward movement of the slide and to conform about fuel lumps engaged in whole or in part beneath the gate so as to prevent sifting through of fine fuel at the sides of said lumps.

30. In a furnace, a fire pot, fuel feeding means for feeding fuel charges into the fire pot, driving means for said fuel feeding means, a first controlling means for the driving means operable to render the fuel feeding means effective for feeding a predetermined definite number of fuel charges into the fire pot in a given interval of time for maximum combustion operation of the furnace, a second controlling means for the driving means operable to render the fuel feed-

ing means effective for feeding a predetermined definite lesser number of fuel charges into the fire pot in the same given interval of time for idling operation of the furnace, means automatically responsive to heat demands during normal operation for rendering said first and second driving means controlling means selectively effective, a third controlling means for the driving means operable as a result of abnormally rapid combustion in the fire pot or incidental to initial making up of a fire in said fire pot to dominate all controls and cause said driving means to render the fuel feeding means effective for feeding successive fuel charges continuously until normal combustion conditions are reestablished, and means including a fan for supplying air for combustion to the fire pot continuously during maximum combustion operation of the furnace and intermittently during idling operation of the furnace.

31. In a furnace, the combination defined in claim 22 in which is included a generally horizontal fuel supporting wall over which the fuel feeding slide travels and which has a terminal edge over which fuel is pushed by the slide into the fire pot, and in which the slide moving means is effective to move the slide always up to said terminal edge on the forward stroke of the slide.

32. In a furnace, the combination defined in claim 22 in which is included a generally horizontal fuel supporting wall over which the fuel feeding slide travels and which has a terminal

edge over which fuel is pushed by the slide into the fire pot, in which there is included a radiant heat shielding gate pivotally suspended directly over said terminal edge, and in which is included means for adjusting the stroke of movement imparted to the fuel feeding slide without altering the advance stroke limit of said slide which remains constant at said terminal edge.

33. In a furnace, a longitudinal fire pot having a receiving end and an end portion over which ash and clinker can be discharged and including fuel mass supporting bottom and fuel mass retaining side walls, a pusher reciprocably mounted at the fresh fuel receiving end of the fire pot remote from said discharge end for advancing fresh fuel charges and fuel mass along the fire pot, a fresh fuel hopper having a discharge throat disposed above and adjacent said receiving end, a fresh fuel charge pushing slide reciprocable at least part way across said throat for feeding successive charges of fuel into the space formed by each retraction of the pusher, driving means for said pusher and slide, means for varying the length of fresh fuel charge feeding intervals, and also means for automatically varying the amount of fresh fuel charges, thereby to supply an amount of fresh fuel which may be held proportional to the combustion capacity of the furnace and in keeping with the variations in the air supply.

HUGH W. SANFORD.
